DESIGN FOR A TIE RACK

Arthur A. Nu-Dell, Chicago, Ill., assignor to Nu-Dell Manufacturing Co., Inc., Chicago, Ill.,
a corporation of Illinois

Application October 13, 1939, Serial No. 87,649

Term of patent 7 years

To all whom it may concern:

Be it known that I, Arthur A. Nu-Dell, a citizen of the United States, residing at Chicago, in the county of Cook and State of Illinois, have invented a new, original, and ornamental Design for a Tie Rack, of which the following is a specification, reference being had to the accompanying drawing, forming part thereof.

Fig. 1 is a front elevational view of a tie rack showing my new design.

Fig. 2 is a plan view of a tie rack showing my new design.

Fig. 3 is a side elevational view of a tie rack showing my new design.

I claim:

The ornamental design for a tie rack, as shown.

ARTHUR A. NU-DELL.
